J. LEDWINKA

CURTAIN SUPPORT FOR AUTOMOBILE DOORS

Filed Jan. 29, 1925

FIG. 1

FIG. 3

INVENTOR.

JOSEPH LEDWINKA

BY *John T. Farley*

ATTORNEY.

UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

CURTAIN SUPPORT FOR AUTOMOBILE DOORS.

Application filed January 29, 1925. Serial No. 5,421.

This invention relates to curtain supports for automobile doors, and more particularly to supports for attaching storm curtains to the doors so that they may be easily opened 5 and closed together with the doors.

Heretofore, it has been the practice to include provisions for moving the curtains with the doors mainly in the more expensive types of automobiles. This has been the case be- 10 cause the devices which have been used for this purpose have been quite expensive due to their complexities of construction. Also some of these devices have been inherent structural features of the doors themselves, thus neces- 15 sitating increased cost of manufacture of the doors as well as increasing the amount of labor necessary to obtain a completed door structure. All of this has precluded the general use of such devices in the cheaper types 20 of cars.

In this latter type of car the curtains have of necessity been fastened into place on the doors and body of the automobile by the use of a plurality of snap fasteners or similar de- 25 vices. When the door of the car is to be opened, it is first necessary to unfasten the curtains therefrom. This is decidedly incon- 30 venient and moreover, it eventually results in prematurely torn or otherwise injured curtains.

It is an object of my invention to provide a means for supporting the storm curtains upon the door which is at once effective as it is ex- 35 ceedingly simple in construction and extremely cheap. It is a further object of my invention to provide a curtain rod support which may be readily applied to a door without in any manner affecting the construction of the door itself.

40 My invention consists in the novel construction, combinations and devices to be herein- after described and claimed for carrying out the above stated objects and other such objects as will appear from the following descrip- 45 tion of a preferred embodiment illustrated in the accompanying drawings, in which

Fig. 1 is an inside view of a portion of the automobile body, showing my support attached to the door thereof;

Fig. 2 is an enlarged view showing the rod 50 supported in the improved socket; and

Fig. 3 is a view on the line 3—3 of Fig. 2.

In general, my invention contemplates the use of a single metal stamping which may be welded or otherwise suitably secured to the 55 inside of the automobile door, this metal stamping being provided with integral means for the reception of the curtain rod. The bodies of these stampings are pressed out of steel sheetings, it having been previously de- 60 termined just what outline is necessary in order to obtain the desired effects. In this particular instance, I prefer to give an outline to the metal stamping such as will provide laterally extending portions or tabs around 65 the periphery of the main body portion there- of. Openings are provided in these laterally extending portions preferably by punching holes therethrough. These apertured tab por- 70 tions are disposed at opposite sides of the main body of the metal stamping and are bent upwardly out of the plane of the main body portion and at right angles thereto so that the openings will be brought into alignment with each other. By this arrangement it becomes 75 possible to insert the curtain rod through the openings so that it is effectually positioned against lateral displacement and so as to prevent any possibility of its remaining in any but its proper position due to the provision 80 of the supporting means at two points in vertical alignment.

In addition to the provision of aligned openings through which the curtain rod ex- 85 tends, I provide a means at the lower end of the support for preventing a too great down- ward movement of the rod therein. In my preferred form of the invention, this means consists in rectangularly shaping the aper- 90 ture or opening in the lower portion of the support so as to neatly receive the lower end of the rod which is reduced in cross-section and which is also of rectangular cross sec- 95 tion. In addition to limiting the downward movement of the rod, such a construction also prevents any rotation thereof in the support.

In the drawings, I have shown a preferred embodiment of my invention and in the fol-

lowing description thereof similar reference characters are used to designate similar parts throughout the several views. My socket or support is generally indicated by 10 and comprises a stamping having a flat main body portion 11 and laterally extending portions 12, 13, 14 and 15 at each side thereof. The portions 12 and 13 are bent upwardly from the plane of the body 11 and substantially 10 at right angles thereto and are provided at their forward ends with cupped apertures or openings 16 and 17, respectively, the latter aperture being provided with a flared portion or lip 21. These openings are in vertical 15 alignment with each other, the upper aperture 16 being of a size sufficient to freely permit passage therethrough of the curtain rod 18. The lower aperture 17 is so designed as to limit the downward movement and to prevent any rotation of the rod in its socket. As 20 is clearly shown in Figs. 2 and 3, the opening 17 is rectangularly shaped to neatly receive the complementally shaped lower end 19 of reduced cross-section of the curtain rod 25 18. By so designing the lower end of the rod a shoulder 20 is provided which is adapted to rest upon the inner surface of the lip 21 of the lower aperture 17, this being clearly shown in Fig. 3. This lip in addition to acting as a support for the shoulder 20 of the curtain rod also acts as a guiding means for seating the lower end of the rod within the cupped aperture 17.

Approximately in the center of the body 30 portion 11 and in alignment with the openings 16 and 17 is provided a projection or protuberance 22 which extends to just within the path of the rod as the latter is inserted into the socket. The purpose of this projection 35 22 is clearly apparent from Fig. 3, it being to force the rod 18 outwardly against the forward edges of the holes 16 and 17 so as to take up any play which might exist between the rod and its supporting structure, the projection also acting as a guide for the rod as it is 40 inserted within the support.

The above described socket or supporting means is preferably secured to the inside of the automobile door preferably by welding, 45 preferably by spot welds indicated as at 25, though it is obvious that other securing means may be used without in any manner affecting the spirit of my invention. Thus, in the case of composite body structures where there is no 50 metal to which the support may be welded, holes may be provided in the body portion 11 through which screws may pass into the wood or other structure. For purposes of welding the support to the automobile body, the laterally extending portion 14 may be angularly 55 disposed with respect to the main body portion so that a lap weld may be made between its outer edge 23 and the side 24 of the door body, while the main body 11 is spot welded to 60 the supporting inner panel.

It will be seen from the hereinabove description of a preferred form of my invention that I have provided a support for a certain rod which is extremely simple and inexpensive to manufacture requiring only the ordinary stamping and punching operations to produce the completed article. Further, the support may be easily and quickly applied to the body of the automobile without affecting the latter's structure. Lastly a support has 70 been devised which is highly efficient in operation and which is not likely to be put out of commission due to dirt and other foreign substances clogging the socket, as so often happens with other more complex types of curtain rod supports, as, for example, the tubular type. 75

I am aware that the embodiment which I have shown and described may be varied considerably without departing from the spirit 80 of my invention and therefore I desire to claim my invention broadly as indicated by the appended claims.

What I claim is:

1. In a curtain rod socket member, a substantially flat body portion adapted to be welded to the inner side of an automobile door panel, an upper portion having an aperture therein for passage of the curtain rod therethrough, a lower portion having an irregularly shaped seat therein for reception of the bottom end of the curtain rod, and a side portion adapted to be welded to the inner side of the end panel of the door, all of said portions being integrally united. 100

2. As an article of manufacture, a blank of pressed steel comprising a polygonal body portion, laterally extending portions on three margins of said body portion, two of said portions having apertures punched therethrough, one of said apertures being of non-circular periphery, and a projection formed substantially in the center of the body portion and extending toward a line joining the apertures. 105

3. A curtain rod socket comprising a substantially flat sheet metal main body having its upper and lower ends inturned and provided with downwardly cupped apertures, the lower of which is of less area than the upper. 110

4. A curtain rod socket stamping comprising a substantially flat sheet metal main body having its lower and upper ends inturned to lie in substantially parallel planes, 120 the upper of which is provided with a circular opening and the lower of which is provided with a polygonal opening of less area.

5. A support for curtain rods comprising a base member, upper and lower projections 125 from said base vertically spaced apart and provided with aligned rod receiving apertures which are adapted to receive said rods by insertion axially of said apertures and positively retaining the same against lateral 130

displacement and in a position free from the body of said base together with a positive projection from the base intermediate the spaced apertures adapted to engage the rod and bind it in the apertures to prevent rattle.

5 6. A one-piece curtain rod socket comprising a substantially flat sheet metal stamping

having its ends turned over in the same direction and provided with aligned apertures to 10 engage a curtain rod and a projection in said stamping to bind the curtain rod in said apertures and prevent rattle.

In testimony whereof I hereunto affix my signature.

JOSEPH LEDWINKA.
